UNITED STATES PATENT OFFICE.

OTTO W. AAGAARD, OF CHICAGO, ILLINOIS.

CUSHION FOR TELEPHONE RECEIVERS

1,426,340.

Specification of Letters Patent. Patented Aug. 22, 1922.

Application filed January 19, 1922. Serial No. 530,379.

To all whom it may concern:

Be it known that I, OTTO W. AAGAARD, a citizen of the United States, and a resident of Chicago, in the county of Cook and State of Illinois, have invented a new and useful Improvement in Cushions for Telephone Receivers, of which the following is a full, clear, and exact description.

My invention relates to improvements in 10 cushions for telephone receivers, and it consists in the combinations, constructions and arrangements herein described and claimed.

An object of my invention is to provide 15 a device of the character described, which may be quickly attached or removed from the ordinary type of telephone receiver now in use.

A further object of my invention is to 20 provide a device of the character described which enables the user to shut out all noises from the outside.

A further object of my invention is to 25 provide a device of the character described of soft rubber having a bearing surface, which entirely encompasses the ear and which is not likely to abuse the ear as in the case of the ordinary type of receiver cap when used consistently.

Other objects and advantages will appear 30 in the following specification, and the novel features of the invention will be particularly pointed out in the appended claims.

My invention is illustrated in the accompanying drawings, forming part of this application, in which—

Fig. 1 is a sectional view of my device applied to the ordinary type of telephone receiver.

Fig. 2 is a side elevation of the device 40 removed from the receiver, and

Fig. 3 is a rear elevation of the device as shown in Fig. 2.

In carrying out my invention, I make use 45 of the ordinary type of telephone receiver having a body portion 1 and a cap 2. The cap 2 is provided with an opening 3 centrally located in a shallow depressed portion 4 of the cap.

The present embodiment of my invention 50 consists in a substantially semi-spherical soft rubber shell 5 having a circular opening 6 in its lower wall.

Means for removably securing the shell 5 in operative position upon the cap 2 of

the telephone receiver 1 is provided in a 55 relatively thin gripping portion 7 which is integral with the shell 5 and which is provided with a reenforcing ring 8 at its lower end. The gripping member 7 is substantially tubular in shape when out of engagement with the cap 2 and is soft and pliable, as shown in Fig. 2.

The upper rim 9 of the shell 5 is provided with a hollow portion 10 extending the entire circumference of the rim and relatively 65 deep in the wall of the shell so that the side walls 11 and 12 of the shell 5 on each side of the hollow 10 are extremely thin. This provides a pneumatic cushion so that when the rim 9 of the shell 5 is placed upon the 70 head as the shell encompasses the ear and pressure is brought to bear thereon, it will tend to seal the rim 9 upon the head, but will not abuse the flesh, since the thin walls 11 and 12 will give and provide a cushion- 75 like bearing of the rim 9 and the head.

A plurality of openings 13, in this case I have shown two, are provided in the shell 5 adjacent the point 14 where the gripping member 7 joins the body of the shell 5. 80

From the foregoing description of the various parts of the device, the operation thereof may be readily understood. The device may be quickly attached or detached from the cap 2 of the telephone receiver 1 by merely stretching the gripping member 7 and passing it over the rounded portions 15 of the cap 2. The reenforced portion 8 acts as a means to pull the lower edges of the gripping member 7 closely together, as 90 shown in Fig. 1. The telephone receiver may now be used in precisely the same manner as before, except that in place of holding the relatively hard cap 2 in direct contact with the ear which not only tires the ear but admits noises from the outside, the shell 5 is held so that it entirely encompasses the ear so that the soft pneumatic portion at the rim 9 lies in close contact with the head adjacent the ear. The openings 13 admit air to 95 the interior of the shell so that the sound waves travelling from the vibrating diaphragm of the receiver 1 are provided with a normal medium, i. e., the air, through which to travel to the ear. If these holes 100 13 are not provided, the air within the shell 5 might be either at low or high pressure or might constantly vary, due to the pres-

105

sure of the rim 9 against the head and the sound waves would not be properly transmitted from the diaphragm 17 to the ear.

I claim:

- 5 1. A device of the character described comprising a substantially semi-spherical soft rubber shell, said shell having a hollow portion in its side walls immediately adjacent the rim thereof and extending around 10 the entire circumference of said shell, said shell having an opening therethrough centrally located in the bottom wall thereof, and means integral with said shell for removably securing said shell to a telephone receiver 15 so that its concave surface faces outwardly and the opening therethrough is adjacent the diaphragm of said receiver.
2. A device of the character described comprising a substantially semi-spherical soft rubber shell, said shell having a hollow portion in its side walls immediately adjacent the rim thereof and extending around the entire circumference of said shell, said shell having an opening therethrough centrally located in the bottom wall thereof, and means integral with said shell for removably securing said shell to a telephone 20 receiver so that its concave surface faces outwardly and the opening therethrough is adjacent the diaphragm of said receiver, said means comprising a soft flexible rubber neck portion extending rearwardly from the convex surface of said shell and having a reinforcing band at its outer edge.
3. A device of the character described comprising a substantially semi-spherical soft rubber shell, said shell having a hollow portion in its side walls immediately adjacent the rim thereof and extending around the entire circumference of said shell, a plurality of vents in the side walls of said shell, said shell having an opening therethrough centrally located in the bottom wall thereof, and means integral with said shell for removably securing said shell to a telephone 25 receiver so that its concave surface faces outwardly and the opening therethrough is adjacent the diaphragm of said receiver.

OTTO W. AAGAARD.
